(57) **CLAIM**

The ornamental design for a fan shaped smoke box, as shown and described.

DESCRIPTION

FIG. 1 is a perspective view of a fan shaped smoke box showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is partially enlarged view of the encircled area 8 in FIG. 1;

FIG. 9 is partially enlarged view of the encircled area 9 in FIG. 2;

FIG. 10 is partially enlarged view of the encircled area 10 in FIG. 3;

FIG. 11 is partially enlarged view of the encircled area 11 in FIG. 4;

FIG. 12 is partially enlarged view of the encircled area 12 in FIG. 4;

FIG. 13 is partially enlarged view of the encircled area 13 in FIG. 7; and,

FIG. 14 is partially enlarged view of the encircled area 14 in FIG. 7.

The broken lines shown in the drawings depict portions of the fan shaped smoke box that form no part of the claimed design. The dot-dash broken lines depict the boundaries of the enlarged views and form no part of the claimed design.

1 Claim, 11 Drawing Sheets
